DRILL PRESS

Lester G. Barfels, Grundy Center, Iowa

Application August 23, 1945, Serial No. 612,195

4 Claims. (Cl. 77—55)

1

This invention relates generally to drill presses and in particular to an attachment for lubricating and cooling a drill bit.

An object of this invention is to provide an improved drill bit oiler attachment.

A further object of this invention is to provide a drill bit oiler adapted to control the supply of oil to the bit in response to the movement of the bit into and out of its top moved position.

Yet another object of this invention is to provide a drill bit oiler which is of a simple and compact construction, adapted to be applied to different types of drilling machines, and operable to automatically supply oil to the drill bit in any moved operating position therefor, and to stop the supply of oil when the bit is moved to its top or normal rest position.

A feature of this invention is found in the provision of a drill bit oiling attachment in which an oil reservoir supported on the drill shaft carriage for up and down movement with the drill bit has an oil outlet in its bottom side connected with a tube for directing oil to the bit. A stationary valve member, supported in the path of movement of the oil reservoir, is adapted to seat against the reservoir outlet, when the drill bit is in its top position, to stop the flow of oil to the bit, with the outlet being moved out of seating engagement with the valve member when the drill bit is moved downwardly away from its top position.

Further objects, features and advantages of this invention will become apparent from the following description when taken in connection with the accompanying drawing in which:

Fig. 1 is a front elevational view of a drill press showing the oil attachment of this invention assembled thereon, and with parts thereof shown in section to more clearly illustrate its construction;

Fig. 2 is a fragmentary elevation view illustrated similarly to Fig. 1 but with parts thereof shown in changed position;

Fig. 3 is a perspective view of the stationary valve member forming part of the attachment of this invention;

Fig. 4 is an enlarged fragmentary sectional view taken on the line 4—4 in Fig. 2; and

Fig. 5 is a fragmentary sectional detail view of the valve member shown in Fig. 3.

With reference to the drawing the drill bit oil-

2

ing attachment of this invention is illustrated in Fig. 1 assembled on a drill press of a usual type including a base 5, an upright column or standard 6 and an upper frame 7 supported on the standard 6 to the forward side thereof. Gearing for operating a drill shaft 8 is arranged within a housing 9 connected to the top of the frame 7 by bolts 10. A carriage 12, for supporting the drill shaft 8, is guidably supported in the frame 7 for up and down movement from its lower side. At the lower end of the drill shaft 8 is a chuck 13 which carries a drill bit 14. The work to be drilled is carried on a table 16 adjustably supported for vertical movement on the standard 6, with the carriage 12 and bit 14 being moved up and down together relative to the work table 16 through a usual hand pressure device including a rotatable operating handle 17.

The oiling attachment of this invention includes an oil reservoir 18 having an open top side and a bottom wall 19 (Figs. 1 and 2). An outlet 21 for the reservoir 18 is extended upwardly through the bottom wall 19 so that its top end 22 is in a spaced relation with the top side of the bottom wall 19 for a purpose which will appear later. Connected to the outlet 21 is a flexible oil conduit 23 having its free end 24 movable to a position adjacent to the drill bit 14. It is seen, therefore, that the outlet 21 constitutes an extension for the oil conduit 23, so that the conduit 23 and the reservoir 18 form a pre-assembled unit.

The reservoir 18 is supported on the carriage 12 for movement therewith, and in turn for movement with the drill bit 14, by means including a bracket clamp 26 (Figs. 1 and 4) extended about the lower end of the reservoir 18 and provided with oppositely arranged clamping members 27. A split collar 28 adapted to be positioned about the lower end of the carriage 12 has split portions 29 received between the clamp members 27. A single bolt 31 extended through the clamping members 27 and the split portions 29, on being tightened, concurrently clamps the collar 28 on the carriage 12 and the bracket 26 on the collar 28.

As best appears in Fig. 1 it is seen that the oil reservoir 18 is movable up and down in a path to one side of the frame 7. By virtue of the support of the reservoir on the carriage 12 the outlet end 24 of the conduit 23 is always maintained

in an adjusted position relative to the drill bit 14 for all moved positions of the bit.

Oil from the reservoir 18 is automatically supplied to the drill bit 14 on its movement downwardly from a top or normal rest position, shown in Fig. 2, and then automatically shut-off when the drill bit 14 is returned to its position shown in Fig. 2, by means of a stationary valve structure 32. The structure 32 comprises a substantially L-shaped member 33 formed of a single piece of a flat bar material bent or twisted at 34 to form a short leg 36 and a long leg 37 (Figs. 1 and 3). The leg 36 has its free end connected by one of the bolts 11 to the frame 1, so that the long leg 37 is extended downwardly in a spaced relation with the frame 1. An extension 38 for the long leg 37 is adjustably supported for up and down movement relative to the leg 37 by bolts 39 extended therethrough and through longitudinally extended slots 41 in the leg 37 (Fig. 5).

The lower or free end of the extension 38 is formed with a lateral projection 42 the bottom side of which is covered with a leather or rubber member 43, or like gasket fluid sealing material. The valve structure 32 is of a shape and size such that the leg 37 and its extension 38 are receivable within the top side of the reservoir 18, with the member 43 positioned in the path of movement of the outlet 21. The extension 38 is adjusted relative to the leg 37 so that when the drill bit 14 is in its top position shown in Fig. 2, the member 43 is in fluid sealing engagement with the top end 22 of the outlet 21 to stop the flow of oil therethrough.

In the operation of the oiling attachment of this invention assume the parts to be in their position shown in Fig. 2, in which the drill bit 14 is at its top position and the member 43 in seating engagement with the top end 22 of the reservoir outlet 21. In this position of the drill bit 14 no flow of oil takes place from the reservoir 18 into the conduit 23. On movement of the drill bit 14 downwardly toward the work table 16 the end 22 of the outlet 21 is moved out of its seating engagement with the seating member 43 so that oil is automatically supplied to the drill bit 14.

Since the oil reservoir 18 and the tube 23 are movable up and down with the drill bit 14, any adjusted position of the tube end 24 relative to the drill bit 14 is maintained at all moved positions of the drill bit. The supply of oil to the bit 14 continues at all moved positions of the bit 14 out of its top or normal rest position. On upward movement of the bit 14 to its top position the outlet 22 is seated against the member 43 to automatically stop the flow of oil through the tube 23.

With the upper end of the outlet 21 spaced above the top surface of the bottom wall 19 of the reservoir 18 dirt and foreign material is permitted to accumulate on the bottom 19 to an appreciable extent without interfering in any way with a fluid sealing engagement of the member 43 and the outlet 21. The work table 16 may be provided with a collecting pan (not shown) so that oil supplied to the drill bit 14 may be returned to the reservoir 18 for reuse.

In some instances of drilling, such as in the drilling of wood, a cooling or oiling of the bit 14 is not required. A valve 44, therefore, is connected in the conduit 23 to close the conduit under such operating conditions. In other words when the valve 44 is closed no oil will flow

through the tube 23 regardless of the relative positions of the seating member 43 and the outlet end 22. It will be appreciated, of course, that the valve 44 may also be used to regulate the rate of flow of oil through the conduit 23, in conjunction with the control of the oil flow by the valve structure 32 as above described.

From a consideration of the above description it is seen that the invention provides an oiling attachment for a drill press which is of a simple and compact construction, and readily applicable to different types of drill presses. The attachment operates automatically to control the supply of oil to the drill bit in response to its movement into and out of a top or normal rest position. Further the attachment is rendered inoperative by the actuation of the valve 44 to provide for the use of the drill in dry drilling operations.

Although the invention has been described with respect to a preferred embodiment thereof it is to be understood that it is not to be so limited since changes and modifications can be made in the parts thereof within the full intended scope of this invention as defined by the appended claims.

I claim:

1. In a drill press having a frame, a vertically movable bit support, a drill bit carried in said support and a liquid reservoir mounted on said drill bit support for vertical movement therewith, means for supplying liquid from said reservoir to said drill bit comprising a tube having one end extended upwardly through the bottom of said reservoir and its opposite end movable to a position adjacent to the drill bit, a stationary valve structure carried at its upper end on said frame and adapted to extend through the top of said reservoir with its lower end adjacent to the bottom of the reservoir when the drill bit is in its top position, and a valve member on the lower end of said structure adapted to seat on the one end of said tube when the drill bit is in said top position.

2. In a drill press having a frame, a vertically movable bit support, a drill bit carried in said support and a liquid reservoir mounted on said drill bit support for vertical movement therewith, means for supplying liquid from said reservoir to said drill bit comprising a conduit connected at one end to the bottom of said reservoir, an extension on said one end projected upwardly into said reservoir, a substantially L-shape valve structure having its short leg connected to said frame and its long leg extended downwardly in a spaced relation with said frame at a position such that said long leg is within the reservoir when said support is moved to the top position therefor, and a valve member at the lower end of said long leg adapted for seating engagement with said extension at the top position of said support to control the flow of liquid through said conduit in response to the movement of said support into and out of its top position.

3. In a drill press having a frame, a vertically movable bit support, a drill bit carried in said support and a liquid reservoir mounted on said drill bit support for vertical movement therewith, means for supplying liquid from said reservoir to said drill bit comprising a conduit having its upper end connected with the bottom of said reservoir, and its lower end movable to a position adjacent to said bit, and a stationary valve member for controlling the flow of liquid through said conduit supported in a spaced relation with said

70
75

frame and in the path of movement of said reservoir, with said conduit upper end being moved into and out of seating engagement with said valve member concurrently with the movement of said bit into and out of its top position.

4. In a drill bit oiling device having a movable oil reservoir supported for up and down movement with a drill bit, means for controlling the flow of oil from said reservoir to said drill bit including an outlet in the bottom of said reservoir, an oil tube connected at one end with said outlet and having its other end movable to a position adjacent to said bit, and a stationary valve member supported in the path of movement of said reservoir such that, when said bit is in its top

15

position, said outlet is seated against said valve member to stop the flow of oil through said conduit, with said outlet being moved away from said valve member, on movement of the bit from said top position, to provide for a supply of oil to said bit.
